CLAIM

The ornamental design for environmental extension for pets, as shown and described.

DESCRIPTION

FIG. 1 is a front, top and left side perspective view of an environmental extension for pets showing my new design; FIG. 2 is a top plan view thereof; FIG. 3 is a front elevational view thereof; FIG. 4 is a right side elevational view thereof; FIG. 5 is a left side elevational view thereof; FIG. 6 is a rear elevational view thereof; FIG. 7 is a bottom plan view thereof; and, FIG. 8 is a perspective shown in use, with the broken line environment being for illustrative purposes only and forming no part of the claimed design.
